UNITED STATES PATENT OFFICE.

BENJAMIN J. HARTMAN, OF WOOSTER, OHIO, ASSIGNOR OF ONE-HALF TO
DAVID W. IMMEL, OF SAME PLACE.

GIG-SADDLE.

SPECIFICATION forming part of Letters Patent No. 319,484, dated June 9, 1885.

Application filed August 29, 1884. (No model.)

To all whom it may concern:

Be it known that I, BENJAMIN J. HARTMAN, a citizen of the United States, residing at Wooster, in the county of Wayne and State 5 of Ohio, have invented a new and useful Gig-Saddle-Spring Fastener, of which the following is a specification.

My invention relates to improvements in gig-saddle-spring fasteners for single-strap harness-saddles. Its object is to provide an improved device for uniting and holding together the several leather parts of a gig-saddle at the lower or outer ends of the pads. I attain this object by the mechanism illustrated 15 in the accompanying drawings, in which—

Figure 1 is a detached gig-saddle-spring fastener embodying my invention. Fig. 2 is a vertical longitudinal section of the same on the line $x-x$. Fig. 3 is a vertical longitudinal 20 section of one side of a gig-saddle cut through the middle and on line $x-x$, showing the relative position of the several parts of the saddle with reference to the spring and fastener.

Referring to the drawings, P is an ordinary 25 gig-saddle spring, at the lower or outer end of which is attached my improved fastener, H, consisting of an upright shank, b, at right angles with the face of the spring, and an upwardly-projecting hook, a. S is the cushion 30 or pad of the saddle; A, the housing for the same. B is the skirt-strap. C is the bearer-strap. D is the loop to secure the bearer, and E is the upper saddle-plate, through which the ring F is secured to the upper end of the 35 spring, as heretofore.

Gig-saddle-spring plates provided with a hook cast thereon have been heretofore used, but always in connection with an upper metal plate to hold the several leather parts of the 40 saddle together upon the hook and pad.

My improvement lies in the situation and construction of a hook upon the pad-plate, in connection with an upper loop, in such a manner as to avoid not only the use of pad-

screws, but also of an upper metal plate to 45 unite and secure the several leather parts, as heretofore; and it consists in placing the hook-fastener H at or near the lower end of the spring-plate P, and constructing it with an outwardly-projecting shank, b, of sufficient 50 length to penetrate through the pad S and skirt-strap B, terminating with a thin, flat hook, a, at an angle with the shank b, and on a line with the face of the plate P, adapted to hold the skirt-strap down securely upon the 55 housing of the pad. The bearer-strap C passes over and conceals this hook, and is held closely and firmly down upon it and the skirt by means of the loop D, which passes under the skirt-strap at the hook a. The several leather 60 parts of the saddle are thus firmly and securely held together and fastened down upon the housing of the pad without the use of any outer metal plate or any pad-screws, as heretofore. By this device the leather parts of the 65 saddle are easily and securely connected and fastened together at the lower or outer end of the pad, and a single-strap gig-saddle produced which is superior in beauty, strength, and durability to any ever before invented. 70

Having thus fully described my invention, what I claim as new, and desire to secure by Letters Patent, is—

In a gig-saddle, the combination, with the 75 pad S, of the spring-plate P, provided with a hook-fastener, H, at its lower end, constructed as shown, and loop D, the hook and loop adapted to unite the several leather parts and secure them upon the pad, without the use of pad-screws or any upper metal plate, 80 substantially as set forth.

In testimony whereof I hereunto set my hand this 22d day of June, A. D. 1884.

BENJAMIN J. HARTMAN.
